END BELL FOR AN EDDY-CURRENT COUPLING
HOUSING OR SIMILAR ARTICLE

Ralph L. Jaeschke, 605 69th St., Kenosha, Wis.

Filed May 13, 1960, Ser. No. 60,580

Term of patent 14 years

(Cl. D26—5)

FIG. 1 is a front elevational view of an end bell for an eddy-current coupling housing or similar article showing my new design;

FIG. 2 is a sectional view taken on the plane indicated by line 2—2 of FIG. 1; and

FIG. 3 is a perspective view to a reduced scale.

I claim:

The ornamental design for an end bell for an eddy-current coupling housing or similar article, substantially as shown.
